UNITED STATES PATENT OFFICE.

EDWARD LONG, OF BURKE, IDAHO.

COMBINATION HAIR AND HAT PIN.

1,266,505.

Specification of Letters Patent. Patented May 14, 1918.

Application filed June 6, 1917. Serial No. 173,202.

To all whom it may concern:

Be it known that I, EDWARD LONG, a citizen of the United States, residing at Burke, in the county of Shoshone and State 5 of Idaho, have invented new and useful Improvements in Combination Hair and Hat Pins, of which the following is a specification.

The present invention relates to a pin capable of being worn in either the hair or hat 10 of the wearer and primarily directed to a novel construction of means for preventing the loss of the pin.

The primary object of the present invention resides in the production of a device of 15 the above stated character, wherein is loosely mounted in the hollow body portion of the pin a locking member capable of being projected exteriorly of the said 20 body for effectively accomplishing the locking action of the pin in engagement with the wearer's hair, consequently, assuring against any accidental loss or displacement 25 of the pin therefrom.

A still further object of the present invention is the provision of a pin of the 30 above stated character which is simple in construction, durable and efficient in use and one which may be manufactured and sold at a comparatively low cost.

With the above and other objects in view, the invention consists in the novel features, 35 details of construction and combination of parts which will hereinafter be more fully set forth, illustrated in the accompanying drawing and pointed out in the appended claim.

Figure 1 is a perspective view of the pin 40 in assembled form; and

Fig. 2 is a longitudinal sectional view through the pin body.

In the illustrative embodiment of the invention, use is made of a hollow pin body 5 preferably constructed of metal, or the like 45 material. The pin gradually tapers in a direction from the open end 6 thereof to provide the pin with the usual tapering pointed end 7, while the material forming the pin is stamped out at points in the length of the 50 pin to provide the same with a plurality of unequally spaced openings 8, 8' and 8'', each pair of openings 8, 8' and 8'' being longitudinally alined with one another and opening out through the opposite sides of the pin 55 body, disposing the openings 8 at a point

adjacent the lower end of the pin, positioning the pair of notches 8' at a point adjacent the upper end of the pin, while arranging the pair of openings 8'' at a point substantially intermediate the former men- 60 tioned pairs of openings.

Loosely mounted within the hollow body portion 5 is a resilient locking member 9 constructed of a plurality of strands of material 10, 11 and 12. The strand of material 65 12 exceeds the length of either the strands 10 and 11, while the strand 11 exceeds the length of the strand 10, consequently upon the intertwisting of the shanks 12 of each of said strands, the pronged ends 13 of the 70 strand 10 are disposed at a point adjacent the head 14 of the locking member; while the pronged ends 15 of the strand 12 are arranged at the outer end of the locking member, and the pronged end 16 of the 75 strand 11 is disposed intermediate the prongs 13 and 15 of the respective strands 10 and 12. When the locking member is moved in a direction toward the pointed end 7 of the body, the prongs 13, 15 and 80 16 will be respectively projected through the openings 8, 8' and 8'' of the body.

Upon the ejection of the prong members of the locking member through the openings of the pin body, the pin will be fas- 85 tened in the hair of the wearer. Manifestly, upon desiring to release the pin from either the hat or hair of the wearer, a pull is given to the locking member for moving the same outwardly of the pin body, which in turn 90 will retract the resilient prongs of the strands within the pin body sufficiently to prevent the entanglement of the locking member with the locks of the hair.

From the foregoing description, taken in 95 connection with the accompanying drawing, the advantages of construction and the method of operation will be readily apparent to those skilled in the art to which the invention relates, and while I have de- 100 scribed the principles of operation of the invention, together with the device which I now consider to be the best embodiment thereof, I desire to have it understood that the device shown is merely illustrative, and 105 that such changes may be made when desired as are within the scope of the appended claim.

What is claimed as new is:—

A pin of the character set forth compris- 110

ing a hollow body portion having a plurality of spaced pairs of transversely alined openings and a locking member for said pin body, said locking member being constructed of a plurality of intertwined strands of material of different lengths, the extremities of each strand presenting resilient

prong members so positioned with respect to the locking member as to facilitate their ejection through the respective openings of the pin body upon movement of the locking member in one direction. 10

In testimony whereof I affix my signature.
EDWARD LONG.
